UNITED STATES PATENT OFFICE.

CHARLES K. BULGARIDES, OF TACOMA, WASHINGTON.

CALKING-MACHINE.

1,334,836.

Specification of Letters Patent. Patented Mar. 23, 1920.

Application filed November 18, 1918. Serial No. 263,033.

To all whom it may concern:

Be it known that I, CHARLES K. BULGARIDES, a citizen of the United States, residing at Tacoma, in the county of Pierce and State of Washington, have invented certain new and useful Improvements in Calking-Machines, of which the following is a specification.

The present invention comprehends generally improvements in that class of inventions known as ships and more particularly relates to a calking machine.

This invention has for its principal object to provide a machine of the above mentioned character designed for calking the spaces between adjacent planks, forming the decking of a ship, or other surface, the component parts being of novel construction to coöperate with each other in such a manner that when the calking material is being fed, desirably, in the form of a string, it is bunched or folded in much the same manner as if fed by hand and is subsequently effectively calked in position.

More particularly, this invention contemplates the provision of a machine of the above mentioned character wherein there is provided plunging or calking means and feeding means, improved actuating means being arranged in connection with the plunging means for moving the feeding means in one direction while acting in conjunction with the feeding means is improved resilient means for insuring of the bunching and folding of the calking material so that it will be immediately and subsequently acted upon by the plunging means and properly arranged in position.

As an additional object, the invention embraces the provision of a machine of the above mentioned character wherein main and secondary frames are provided, the main frame being adjustable so as to vary the distance between the main frame and the decking while resilient means are interposed between the main and secondary frames for yieldingly supporting the secondary frame, and this resilient means in addition acts as a shock absorber for the plunging means.

A still further object of this invention is to provide a machine of the above mentioned character wherein the feeding means is of novel construction and is adjustably supported from the secondary frame and positioned beneath the main frame as well as the plunging means and the said feeding means

is incidentally designed so that it may be locked in an inactive position without interfering with the independent operation of the plunging means, should it be desired to use 60 the machine in such manner.

More specific objects of this invention may be said to consist in the provision of a machine of the above mentioned character wherein guides are employed for engagement with the groove or space between the planks forming the decking for consequently keeping the machine in the proper position as it is being moved forwardly and operated; to provide feeding means wherein the guiding or bunching means and the feeding finger are of novel construction; to improve the construction of the shoes of the feeding means so that they will effectively insure of the movement of the feeding means in one direction when engaged by the reciprocating actuating or operating arms; and to also provide improved means for mounting and actuating the calking tool and the actuating arms.

Among the other aims and objects of the present invention may be recited the provision of a machine of the above mentioned character, comparatively simple in construction, durable, and one which will be very 85 efficient and useful in operation.

With the above and other objects in view, the invention accordingly consists in the novel features of construction, combination and arrangement of parts as will be herein-after referred to and more particularly pointed out in the specification and claims.

The invention is clearly illustrated in the accompanying drawings, in which:—

Fig. 1 is a side elevation of the improved machine.

Fig. 2 is a front end elevational view thereof,

Fig. 3 is a rear end elevational view of the improved machine,

Fig. 4 is a bottom plan detail of the feeding means,

Fig. 5 is a cross sectional detail on line 5—5 of Fig. 4 in a direction in which the arrows point,

Fig. 6 is a plan detail of the feeding finger,

Fig. 7 is a side elevational detail of the same,

Fig. 8 is a side elevational detail of the 110 plunging rod and the actuating arm,

Fig. 9 is an end elevational view thereof,

Fig. 10 is a front elevational detail of the calking chisel.

Fig. 11 is a side elevational view of the same, and

5 Fig. 12 is a fragmentary perspective detail of one of the sides of the feeding mechanism showing the guide therein.

Similar characters of reference are employed in all of the above described views, to 10 indicate corresponding parts.

Referring now, more particularly, to the accompanying drawings there is provided a main frame preferably of a rectangular configuration consisting of side bars 1 connected 15 by a front cross bar 2 and a rear cross bar 3. Arranged between the rear portion of the frame are bearing plates 4 in which is journaled an axle 5 having supporting rollers or 20 wheels 6 mounted thereon while elongated bolts 7 are adjustably arranged through the respective ends of these bearing plates and through the adjacent side bars 1 and the rear cross bar 3 being in turn engaged by nuts 8 which coöperate with the plates and the side 25 and end bars for adjustably mounting the rear portion of the frame with respect to the deck 9. In supporting the front end of the frame spaced bearing blocks 10 are adjustably mounted on the front cross bar 2 30 being rigidly held at various adjusted positions by means of set screws 11. These blocks 10 are formed with vertical bores in which are mounted the threaded portions 12 of supporting legs 13 to the lower ends of 35 which are rigidly fastened brackets 14 while supporting rollers 15 are journaled in these brackets and are of course engageable with said deck 9. Suitable adjusting elements such as nuts 16 are mounted on the threaded 40 portions 12 of the legs and act as bearings contacting with the upper and lower edges of the bearing block 10 for insuring of the maintenance of the legs in the properly adjusted positions. By this construction it is 45 apparent that the forward portion of the frame is adjusted with respect to the deck.

As intimated, there has been provided a secondary frame generally indicated by the numeral 16. In reducing this feature of the 50 invention to practice the frame may be said to consist of a pair of substantially U-shaped supports comprising an intermediate portion which constitutes a cross bar 17 and spaced standards 18 while bracket arms 19 project 55 outwardly at right angles preferably from the upper and lower ends of these standards. A platform 20 is supported upon and secured to the cross bar 17. Opposed pairs of vertical rods 21 rise from the side bars 1 of 60 the main frame near the ends thereof and are engaged by the brackets 19 while disposed about these rods and positioned respectively between the side bars 1 and the lower brackets and between the upper brackets 65 and adjustable elements such as nuts 22

mounted on the upper ends of the rods 21, are coiled springs 23 and 24. These springs serve to yieldably support the secondary frame with respect to the main frame and in addition serve as a means for absorbing 70 shocks likely to be transmitted to the calking chisel in a manner that will hereinafter become apparent.

With a view toward providing the improved plunging or calking means proper a 75 standard 25 is mounted on the platform 20 while also mounted on the platform directly in advance of the standard is a casing 26 desirably of a rectangular configuration the side walls of which are formed with opposed 80 slots 27 while the front wall is provided with spaced vertical slots 28 for a purpose that will presently appear. A shaft 29 is rotatably mounted in the upper end of the standard 25 while carried by one end of the 85 shaft and positioned within the casing 26 is a disk 30. A pin 31 extends eccentrically from the outer face of the disk 30 and is formed with a head 32. This headed pin is arranged in engagement with a correspondingly formed transverse or diametrical slot 33 provided in the adjacent face of another disk 34. A plunger rod 35 is secured by suitable fasteners 36 vertically of the opposite face of the disk 34 and is slidably arranged through opposed openings in the top of the casing 26 and in the platform 20. By this construction it will be apparent that when the shaft 29 is rotated owing to the pin and slot connection between 100 the disks 30 and 34 and the slideable mounting of the plunger rod 35, the latter will be reciprocated during the rotation of the shaft 29. A chuck head 37 is formed on the lower end of the plunger rod 35 and receives the 105 calking tool generally designated by the numeral 38 in the present instance in the form of a chisel having a shank 39 formed on its upper end with a head 40 which is receivable in the chuck while the outer edge 110 of the engaging end of this chisel is curved longitudinally as at 41 and transversely as at 42 this construction serving to insure of an effective tamping or calking of the calking material in a manner that will hereinafter become apparent. A counterbalancing weight in the form of a ball 43 is detachably connected to the upper projecting 115 end of the plunger rod 35. Actuated with the plunger rod and positioned forwardly of the casing and vertically slideable through openings in the platform 20 are spaced actuator arms 43 for the feeder mechanism. Connection is preferably maintained between these arms by means of bracket arms 120 44 the outer ends of which are detachably fastened by suitable fasteners such as screws 45 to the upper ends of the arms while the inner ends are fastened as at 46 to the rod 35, the medial portions being slideable through 125 47 the actuator arms 43. The actuator arms 43 are 130

the slots 28 in the front wall of the casing 26. The lower ends of the arms 43 are enlarged and inclined from their outer edges to their inner edges as indicated by the numeral 47, for a purpose that will hereinafter become apparent.

In order to operate the chisel and the arms a motor 48 is preferably mounted on the rear part of the platform 20 while the shaft 49 thereof is preferably connected to the shaft 29 by means of a coupling generally indicated by the numeral 50. The coupling may be said to consist of a disk 51 mounted on the shaft 49 and a disk 52 mounted on the shaft 29, the said disks being detachably connected to each other by means of suitable fasteners such as bolts 53.

For the purpose of providing suitable means for supporting the calking material a pair of spaced and upwardly curved arms 54 are employed the lower ends being formed with clamps 55 which are disposed about the front cross bar 2 of the main frame and held in adjusted position by means of suitable fasteners such as set-screws 56. The upper ends of the arms are enlarged and formed with opposed recesses 57 in which is journaled a shaft 58 while mounted on this shaft is a drum 59 about which is wound in strip-like form the calking material 60 which may be and preferably is of oakum.

As intimated, improved mechanism has been provided for feeding the calking material rearwardly so that it will be acted upon by the calking chisel. In reducing this feature of the invention to practice, a frame generally indicated by the numeral 61 is positioned beneath the forward ends of the main frame and preferably consists of spaced sides 62 the upper portions of which are joined by a bearing 63 through the vertical bore of which is disposed the threaded portion 64 of a shank 65 which depends from the platform 20 of the secondary frame. Adjustable elements such as nuts 66 are engaged on the threaded portion 64 of the shank and positioned above and below the bearing and serve as a means for adjustably supporting the bearing on the shank. Guides 67 and 68 are carried by the sides 62 of the frame and depend therefrom being positioned at the rear and near the forward ends of the bars and also arranged in engagement with the sides of the groove 69 serving to guide the feeding mechanism as the machine is moved forwardly. Spaced ears 70 extend outwardly from the sides 62 at the ends and approximately medially of the ends thereof while rods 71 are slidably arranged in the ears and positioned preferably parallel with each other and with the bars and also on the outside of the bars or sides of the frame. A cross plate 72 is preferably detachably connected to the forward ends of the rod 71 as by screws 73

and is formed with an opening 74 and with opposed horizontal recesses 75 which communicate with the opening while slidably arranged through this opening 74 is an actuator rod 76 the inner end of which is swiveled as at 77 to a cross bar 78 in turn detachably connected as by fasteners 79 to the forward ends of the side of the frame 61. A knob 80 is carried by the front end of the rod 76 to facilitate the adjustment or turning of the rod so that the opposed lugs 81 on the rod may be engaged by the recesses 75 when the cross plate 72 is pulled forwardly, the rod being subsequently partially rotated so that the lugs will act as a stop or lock and engage the rear face of the plate 72 to hold the rod forwardly for a purpose that will hereinafter become apparent. A pair of shoes 82 are arranged in opposed relation with respect to each other and are rigidly mounted on the slidable rods 71 and are provided with downwardly inclined rear faces 83 which are positioned at times beneath the correspondingly inclined edges 47 of the actuator arms 43 so that when the actuator arms move downwardly the shoes will be forced forwardly. A feeder finger 84 is positioned between the arms and is formed with a widened inner end 85 the side edges of which are arranged in close relation with the inner surfaces of the shoes while suitable fasteners such as screws 86 are engaged through the outer sides of the shoes and in the finger for the mounting of the finger between the shoes. The finger of course moves with the shoes and is positioned beneath the calking material or oakum 60. Coacting with the actuator arms is improved resilient means in the form of coiled expansion springs 87, said springs being disposed about the rear portions of the rods 71, one end of each spring being anchored to the rod as at 88 while the opposite end bears against the ear 70. By this construction it will be apparent that when the actuator arms 43 leave the shoes 82, the springs 87 will act to immediately draw the rods 71 and consequently the shoes 82 and the finger rearwardly, the finger drawing a new bunch of calking material 60 with it and at the same time forcing the material between the opposed guides or recesses 89 formed on the inner faces of the sides 62 of the frame 61 so as to bunch the material or substantially fold the material in a manner much the same as is done by hand and position the said material above the space between the sides 62 and near the guide 67, or directly beneath the chisel 38 so that when the latter subsequently moves downwardly the material will be jammed or calked in position in the groove 69 so as to effectively fill the groove. In calking a vessel it is sometimes the case that the first layer of calking material is placed in a strip-like form and in

order that the plunging or calking means may be operated independently of the feeding and bunching means, it is only necessary to engage the plate 72 and move it forwardly so that it may be engaged with the lugs 81 on the rod 80 and thereby locked in a forward or inactive position.

Coöperating with the groove engaging guides 67 and 68 is another guide 90, the threaded shank 91 of which is arranged through a bearing block 92 in turn adjustably mounted on the rear cross bar 3. A set-screw 93 serves to maintain the bearing block 92 in position while suitable adjustable elements such as nuts 94 are mounted on the threaded shank 91 to coöperate with the block 92 and maintain the shank 91 of the guide 90 in a properly adjusted position relative to the decking. A bracket 95 is preferably connected to the shank 91 of the guide 90 while journaled in this bracket is a supporting roller 96 for insuring of a proper actuation of the guide and maintaining it in a proper position within the groove 69.

To facilitate the manipulation of the machine, gripping handles 97 are connected to the top of the casing 26 and the rear U-shaped support of the secondary frame.

The mode of operation of the present invention may be reviewed as follows:

Assuming that the parts have been assembled in the manner described and as illustrated in the drawings when the motor 48 is started rotary motion will be transmitted thereby to the shaft 29 to rotate the disk 30 and by reason of the eccentric connection of the headed pin 31 and its sliding engagement in the slot 33, the disk 34 will be reciprocated to consequently reciprocate the plunger in a vertical direction and thereby insure of a proper reciprocation of the calking chisel 39 as well as the actuator arms 43 which are connected to the plunger rods 45 as is apparent. Now when the actuator arms 43 move downwardly the inclined faces 47 will engage the inclined faces 83 of the shoes 82 to slide the rods 71 forwardly against the tension of the springs 87. As soon as the arms 43 start on their upward stroke, the springs 87 will act to draw the rods 71 and shoes 82 rearwardly, the finger 84 which is movable with the shoes of course, drawing a new bunch of calking material and forcing it through the guides 89 so as to bunch or fold the material in much the same manner as if done by hand, the guides positioning the bunched material directly beneath the calking chisel 38 so that when the latter moves downwardly on its next stroke the bunched material will be forced through the space between the sides of the frame 61 into the groove 69 to ultimately insure of an effective calking of this groove or space between the planks forming

the decking 9. During the operation of these parts the machine of course is being moved forwardly over the deck and is guided in its movement by the guides 67, 68 and 90 which insure of the working parts being arranged over the groove 69 at all times. In connection with the foregoing, it is to be understood that the springs 23 and 24 which yieldably support the secondary frame also act as recoil springs taking shock of the chisel 38 off of the machine. To permit of the independent operation of the calking chisel it is only necessary to arrange the plate 72 in a forwardly locked position behind the lugs 81 thus locking the feeding mechanism in inactive position. This is done at times when the first piece of material is laid in the groove 69.

It is believed in view of the foregoing description that a further detailed description of the operation of the invention is entirely unnecessary. Likewise it is believed that the advantages of the invention will be readily apparent.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having thus fully described this invention, what is claimed as new and desired to be secured by Letters Patent, is:

1. A calking machine including a movably and yieldingly mounted support, a vertically reciprocatory plunger rod operably mounted on the support, a calking tool carried by the lower end of the rod, means for supporting calking material on the support, horizontally movable feeding mechanism suspended from the support and through which the calking material is trained, actuating members connected to and operable with the plunger rod for moving the feeding mechanism in one direction so that the feeding mechanism will engage a fresh supply of calking material, and resilient means coöperating with the feeding mechanism for moving the feeding mechanism in an opposite direction to advance and bunch the calking material beneath the calking tool so that the material will subsequently be acted upon by the calking tool.

2. A calking machine including a movably and yieldingly mounted support, a ver-

tically reciprocatory plunger rod operably mounted on the support, a calking tool carried by the lower end of the rod, means for supporting calking material on the support, 5 horizontally movable feeding mechanism suspended from the support and through which the calking material is trained, actuating members connected to and operable with the plunger rod for moving the feeding mechanism in one direction so that the feeding mechanism will engage a fresh supply of calking material, resilient means 10 cooperating with the feeding mechanism for moving the feeding mechanism in an opposite direction to advance and bunch the calking material beneath the calking tool so that the material will subsequently be acted upon by the calking tool, and means depending from the feeding mechanism and 15 the support for guiding the machine during movement.

3. A calking machine including a movably and yieldingly mounted support, plunging means operably mounted on the support, means for supporting calking material on the support, horizontally movable mechanism suspended from the support for feeding the calking material beneath the plunging means so that it will be acted upon 20 by the plunging means, means operable with the plunging means for acting against the feeding mechanism to move said mechanism in one direction, resilient means 25 cooperating with the actuating means for advancing the feeding mechanism in the opposite direction, and means for locking the feeding mechanism in an inactive position and against the tension of the resilient means whereby to permit of the independent 30 operation of the plunging means when desired.

4. In a calking machine, the combination with a support, and a vertically reciprocatory calking tool mounted thereon, of mechanism suspended from the support for feeding and bunching calking material beneath the calking tool, said mechanism including a frame, a feeder finger slidable on the frame, means for sliding the finger in one direction so that it will engage a fresh supply 45 of calking material, resilient means mounted in the frame and coöperating with the finger for moving the finger in the opposite direction so that the finger will advance the calking material into a position beneath the calking tool whereby to permit of the calking of the material into position by the calking tool.

5. In a calking machine, the combination with a movably and yieldingly mounted support, a vertically reciprocatory calking tool mounted on the support and actuators movable with the calking tool, of mechanism 50 for feeding calking material including a frame suspended from the support, shoes

slidably mounted on the frame and disposed beneath the actuators so as to be engaged by the actuators and slid in one direction, a feeder finger mounted between the shoes and movable therewith so as to engage a fresh supply of calking material, and resilient means 70 mounted in the frame and coöperating with the shoes for moving the shoes in an opposite direction to advance the finger and position calking material beneath the 75 calking tool so that the material will subsequently be engaged and forced into position by the calking tool.

6. In a calking machine, the combination with a movable and yieldingly mounted support, a vertically reciprocatory calking tool mounted on the support and actuators movable with the calking tool, of mechanism for feeding calking material including a frame suspended from the support, shoes 80 slidably mounted on the frame and disposed beneath the actuators so as to be engaged by the actuators and slid in one direction, a feeder finger mounted between the shoes and movable therewith so as to engage a fresh supply of calking material, resilient means 85 mounted in the frame and coöperating with the shoes for moving the shoes in an opposite direction to advance the finger and position calking material so that it will subsequently be engaged and forced into position by the calking tool, and guides depending from the frame for guiding the feeding mechanism during movement.

7. In a calking machine, the combination with a movable and yieldingly mounted support, a vertically reciprocatory calking tool mounted on the support, and actuators connected to and movable with the calking tool, of mechanism for feeding calking material 100 including a frame adjustably suspended from the support, calking material guides carried by the frame, shoes slidably mounted on the frame and engageable by the actuators so as to be slid in one direction, a feeder finger mounted between the shoes and movable therewith so as to engage a fresh supply of calking material, resilient means 105 mounted in the frame and coöperating with the shoes for moving the shoes in an opposite direction to advance calking material into a position beneath the calking tool, the finger insuring of the material passing through and being bunched by the guides so that the material will subsequently be engaged and effectively forced into position by the calking tool.

8. In a calking machine, the combination with a movably and yieldingly mounted support, a vertically reciprocatory calking tool mounted on the support and actuators connected to and movable with the calking tool, of mechanism for feeding calking material 115 including a frame suspended from the support, calking material guides carried 120

by the sides of the frame, rods slidably mounted in the frame and positioned exteriorly of the sides thereof, shoes connected to the rods, a feeding finger connected between the shoes, the shoes being positioned so as to be engaged by the actuators and thereby moved in one direction so that the feeder finger will engage a fresh supply of calking material, springs disposed about and connected to the rods and exerting a tension on the rods so as to move the rods and consequently the shoes and finger in an opposite

direction so that the finger will advance and force the calking material between the guides to insure of the bunching or folding of the material preparatory to the forcing of the material into position by the calking tool, and other guides depending from the frame for guiding the feeding mechanism during forward movement of the calking machine. 15

20 In testimony whereof, I affix my signature hereto.

CHARLES K. BULGARIDES.
